(57) **CLAIM**

The ornamental design for a pet fetching device, as shown and described.

DESCRIPTION

FIG. 1 is an isometric view of a pet fetching device showing our new design.

FIG. 2 is a bottom perspective view thereof.

FIG. 3 is a left side view thereof.

FIG. 4 is a right side view thereof.

FIG. 5 is a front view thereof.

FIG. 6 is a back view thereof.

FIG. 7 is a top view thereof; and,

FIG. 8 is a bottom view thereof.

The broken lines shown in the Figures show portions of the pet fetching device that depict environmental subject matter only and form no part of the claimed design.
